CLAIM

The ornamental design for an aromatherapy humidifier, as shown and described.

DESCRIPTION

FIG. 1 is a front perspective view of the aromatherapy humidifier showing my new design.

FIG. 2 is a front view of the aromatherapy humidifier.

FIG. 3 is a rear view of the aromatherapy humidifier.

FIG. 4 is a left side view of the aromatherapy humidifier.

FIG. 5 is a right side view of the aromatherapy humidifier.

FIG. 6 is a top view of the aromatherapy humidifier.

FIG. 7 is a bottom view of the aromatherapy humidifier; and, FIG. 8 is a rear and bottom perspective view of the aromatherapy humidifier.

Any shading and cross-hatching are not features of the design but are utilized to illustrate the surface contours of the aromatherapy humidifier design in the drawings.

The broken lines shown in the figures are for the purpose of illustrating portions of the aromatherapy humidifier and form no part of the claimed design.
